UNITED STATES PATENT OFFICE.

CHARLES G. CURTIS, OF NEW YORK, N. Y., ASSIGNOR, BY MESNE ASSIGNMENTS, TO
GENERAL ELECTRIC COMPANY, A CORPORATION OF NEW YORK.

ELASTIC-FLUID TURBINE.

1,027,697.

Specification of Letters Patent. Patented May 28, 1912.

Application filed November 12, 1906. Serial No. 342,956.

To all whom it may concern:

Be it known that I, CHARLES G. CURTIS, a citizen of the United States, residing in the borough of Manhattan, in the city, county, and State of New York, have invented a certain new and useful Improvement in Elastic-Fluid Turbines, of which the following is a description.

The object I have in view is the production of an elastic fluid turbine, which will have certain advantages over those heretofore suggested.

The invention is applicable particularly to turbines for marine use, having a horizontal shaft and being of the axial flow or parallel flow type, but its use is not so limited.

The invention comprehends the use of a plurality of stages each of which contains a plurality of rows of moving buckets alternating with fixed nozzles, but the invention may be carried out with but a single stage. Each nozzle is adapted to convert a certain portion of the pressure belonging to that stage into velocity.

In order to get the proper theoretical conditions in a turbine employing alternate rows of annular nozzles and moving buckets, the buckets and nozzles in the initial stages will have to be undesirably shallow or else the rotating element in the initial stages must be much smaller in diameter than in the succeeding stages. Such turbines are objectionable therefore in having the early stages of too small a diameter or with too shallow buckets.

An object of this invention is to avoid these objections and to permit the rotating element to be of practically uniform diameter throughout, and at the same time without undesirable shallowness of buckets in the initial stage.

The drawings illustrate one form of mechanism for carrying out my invention.

Figure 1 is a view partly in section of one stage of a turbine embodying my invention; Fig. 2 is a development of the nozzles and moving buckets shown in Fig. 1; and Fig. 3 is a view partly in section, but upon a reduced scale, at right angles to Fig. 1.

In all the views, like parts are designated by the same reference characters.

As shown in Fig. 1, the turbine is formed with the shell 1, within which the wheel 2 rotates. The shell is divided into stages by

means of diaphragms 3, and the end of the shell is covered by a head 4. The space between the head and a diaphragm, or between successive diaphragms, constitutes a stage. Within each stage are alternate rows of buckets and fixed nozzles. The first nozzle in a stage is carried by the head 4 or a diaphragm 3, as shown. The successive nozzles 6-6 are shown as supported from a block 7, secured to the shell 1. Other means than that illustrated may be used for supporting the nozzles. Between the nozzles are the rows of moving buckets 8. These buckets, as is customary, are closed in with rims. The depth of the nozzles and moving buckets should be properly proportioned, so as to provide for the increased volume of motive fluid as it passes through the stage. A correct proportioning of the parts is shown in my application for patent filed August 24, 1905, Serial No. 275,623. The nozzles, as shown in Fig. 3, extend around a portion only of the periphery of the shell 1. The amount which the nozzles extend around the periphery of the shell varies, and is less toward the admission end of the turbine than toward the exhaust end. They may also increase in peripheral length within each stage, the successive rows of nozzles toward the exhaust increasing in peripheral length. As a typical form of construction, the nozzles in the first stage, of six or more stages, may occupy about $\frac{1}{4}$ of the periphery of the shell, while the last stage may extend all the way around. This is for the purpose of permitting a greater depth of nozzle and moving buckets for the high pressure stages, and a less depth of nozzles and buckets for the low pressure stages.

The block 7 is shown as making a tight joint with the nozzle 5. This prevents leakage of steam from the nozzle up into the shell, above the nozzles. The leakage toward the center of the shell is prevented by means of a lip 9, which stands close to an annular flange, formed within the rotating element. This lip 9 may be unadjustable or adjustable, and may be similar to that disclosed in my Patent No. 725,032. There will be a certain leakage of steam around this lip, but the amount of leakage will be small. There will also be a certain amount of leakage at the front and back ends of the nozzles, but this leakage will be small. The steam leaking

into the casing around the lip 9 and at the forward and back ends of the nozzles, will pass into the other side, that is, the discharge end of the stage, by any suitable means, such as through the tube 10 shown as formed in the rotating element. Some steam will escape around the upper edge of the first row of moving buckets, but it will be caught and will be compelled to pass through the second nozzle, therefore no steam can escape in this direction into the shell. There will be some leakage of steam after it passes through the first row of moving buckets around the lower edge of the first of the nozzles 6. The steam, however, has no opportunity to escape except through the second row of buckets 8, where it can do useful work.

It will be seen that the steam is quite closely confined to the passage through the nozzles and only a very small proportion of it can escape. The greater portion of the steam must pass through the nozzles and moving buckets. None can pass upward into the shell and very little will pass out at the front and back ends of the nozzle and in toward the center of the shell. Whatever steam, however, leaks at this point in any stage will be recovered in that stage, and may be utilized in succeeding stages. But a small proportion of steam will leak by the top of the first row of buckets, and that steam will be caught and will be utilized in the second nozzle. A still smaller portion of steam will pass around the bottoms of the succeeding nozzles, and that steam will be utilized in the successive rows of buckets. After the steam has passed through the moving and stationary elements of the turbine, it will be collected in the discharge end of the stage in front of the diaphragm 3, and will then discharge through the nozzle 5 into the next succeeding stage.

The invention is not limited to turbines in which the pressure is confined within the shell and an equal conversion made in each nozzle, but on the contrary, the amount of conversion in the nozzles may not be uniform. As an example, where three nozzles 5, 6, 6 are shown, each may develop equal energies or 33½% each. As another example, the nozzle 5 may develop 50% of the total energy in the stage, and the first of the nozzles 6, 30%, and the second of the nozzles 6, 20%, in which case the two nozzles 6, 6 will function partly as nozzles and partly as guide buckets. These figures are solely for the purpose of illustration, as I do not confine myself in any way to the amount of conversion of each nozzle.

The number of nozzles and moving buckets in each stage may be modified, if desired, those shown being for purposes of illustration only. Furthermore, the invention is not to be limited to a stage turbine, as all of

the moving buckets may be made within a single stage.

An advantage of my invention, over turbines in which the velocity is nearly all produced by the nozzle at the beginning of the stage is an improved efficiency. This is caused by an equalization of the velocities in all buckets, because the nearer the velocity is evenly divided among the several rows of buckets, the greater is the efficiency. A further advantage is that the buckets and intermediate nozzles may be all of the same shape, thus reducing the expense of construction, and simplifying repairs and replacements.

It may be found preferable to arrange the nozzles to occupy less than the whole of the periphery of the wheel in the higher pressure stages only, as the peripheral length of the nozzles will increase toward the exhaust. At a certain point in the turbine these nozzles may extend all the way around the shell so as to discharge in a continuous annular sheet.

The invention may be used in connection with turbines employing any elastic fluid as a motive power, steam being chosen solely as an illustration.

In accordance with the provisions of the patent statutes, I have described the principle of my invention, together with the apparatus which I now consider to represent the best embodiment thereof; but I desire to have it understood that the apparatus shown is merely illustrative and that the invention can be carried out in other ways.

Having now described the nature of my invention and the manner in which the same is to be performed, what I claim as my invention and desire to secure by Letters Patent is:

1. An elastic fluid turbine, having a stage composed of a plurality of rows of nozzles and rows of moving buckets alternately arranged, the nozzles extending around less than the whole periphery, and an annular lip for reducing leakage of motive fluid from the first nozzle into the shell, the remaining nozzles being so arranged as to leave no open space between themselves and the shell, and closely approaching the moving element of the turbine to reduce leakage over the ends of the nozzles.

2. An elastic fluid turbine having a stage in which a certain portion of the expansion takes place in the working passage beyond the nozzle, the said nozzle extending around less than the whole periphery, and means for confining the fluid at the clearances to restrict its escape into the shell until it has left the working passage.

3. An elastic fluid turbine having a shell, a nozzle at the beginning of a stage, so formed as to have a considerable end pres-

sure, a certain portion of the expansion taking place in the working passage beyond the nozzle, the said nozzle extending around less than the whole periphery, and means 5 for confining the fluid at the clearances so as to partially prevent its escape into the shell until it has left the working passage.

This specification signed and witnessed this seventh day of November, 1906.

CHARLES G. CURTIS.
